PHONOGRAPH APPARATUS

Frank Rieber, Los Angeles, Calif., assignor to
Memovox, Incorporated, Cleveland, Ohio, a corporation of Ohio

Application November 27, 1939, Serial No. 306,244

9 Claims. (Cl. 274—13)

This invention relates to the recording and reproduction of sound; and especially apparatus of the type that includes a stylus carrying head for embossing or cutting a record on a blank, forming a sound groove, as well as a playback or reproducer head utilizing a needle or stylus affected by the record.

In general such apparatus is well-known. It is one of the objects of this invention to improve apparatus of this character.

It is another object of this invention to improve the quality of recording and reproduction.

It is preferred to utilize, for the record carrying blank, a thin disc made from material that may be readily impressed by an embossing recording stylus. The record groove accordingly is in the form of a continuous spiral of increasing radius as the edge of the disc is approached. It is clear that if the turntable that supports the record disc be rotated at uniform angular speed, there would be a great variation of linear speed from the inner to the outer edge of the record. It has been proposed in the past, to drive the table at a speed ensuring substantial linear speed constancy, whereby the quality of the record is improved. It is another object of this invention to provide an improved drive of this character.

It is another object of this invention to make it possible to interlink the motion of the reproducing or playback head with that of the recording head, in a simple and effective manner; and further to make it possible to adjust the lag of the reproducer head from the recorder head. In this way, whenever a playback is desired of the immediately preceding recorded matter, the playback head is in proper position to accomplish this result without the necessity of moving the head.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

45 The phonograph apparatus may be provided with a turntable 1, shown in this instance as mounted for rotation on a vertical axis and supporting a thin record carrying disk 2. Thus for example as shown most clearly in Fig. 10, the turntable 1 may be fastened as by the aid of a set screw 3 to the upper end of the spindle 4. This spindle 4 may be appropriately supported in spaced ball bearing structures 5 and 6. The upper ball bearing structure 5 for example, may

50 have its inner race urged against a shoulder on

the spindle 4. Its outer race may be accommodated within a boss 7 that may be formed integrally with the frame member 11 (Figs. 2 and 8).

This frame member 11 is shown as one of three spaced frame members 9, 10 and 11 (Figs. 8 and 9) forming the main support for the apparatus. These frame members may be ribbed or otherwise reinforced castings, joined together as by a series of bars 12, 13 (Figs. 2, 6 and 8), which pass through appropriate apertures in all three frame members, and adjacent both the right and left edges of the frame as viewed in Fig. 2. These bars 12 and 13 are shown as round in this instance, and as clamped between the split ears 14, 15, provided in each of the frame members 9, 10 and 11. The top member 21 (Figs. 1, 6, 9 and 10) may overlie all of the three frame members 9, 10 and 11 and may be appropriately fastened to the upper coplanar surfaces of these frame members.

The lower ball bearing structure 6 (Fig. 10) for the spindle 4 is shown as having an inner race, held against a shoulder on the bottom of the spindle 4 as by nut 16. Its outer race is shown as accommodated in a boss 17, also formed integral with the intermediate frame member 11.

The record member 2 may be of the form described in a prior application filed in the name of Frank Rieber, on September 19, 1939, having Serial No. 295,613, and entitled "Sound record carrier." This record disc 2 is shown as held in place on the table 1 by the aid of a button or cap 18 (Figs. 1, 2, 6, 9 and 10). The button 18 may have a comparatively wide flange 19 to which are fastened one or more pins 20. These pins 20 extend downwardly through matching apertures in the record disc 2 and in the table 1.

The manner in which rotation is imparted to spindle 4 will be described in detail hereinafter.

A recording head is utilized for the recording function. The structure of the recording head is shown to best advantage in Figs. 1, 2, 5 and 9. This recording head includes a stylus 22 adapted to contact with the record disc 2. It is shown as held within an electromagnetic recording unit 23, which may be fed in any appropriate manner with electrical impulses corresponding to the sounds to be recorded. Since all this is well understood, further explanation of the operating parts of the unit 23 is unnecessary. The stylus 22 may be arranged to form either a lateral or a hill and dale type of record.

The unit 23 is shown as joined to a frame or body 24. This frame or body 24 is shown as pivotally supported between the arms 25 and 26 of a forked supporting member 27. In the present instance this pivotal support is formed by the aid of a pair of balls 28 (Fig. 5) accommodated in cooperating shallow recesses formed on the sides of the frame 24 and on the inner ends of the pivot screws 29. The weight of the pivoted structure is purposely made such as to ensure a proper recording effect upon the record disc 2, as by an embossing process.

The support 27 is arranged to be advanced as the recording progresses from near the axis of the spindle 4 toward the periphery of the record disk 2. This direction is indicated by the arrow 30 in Fig. 1. For this purpose the support 27 is joined to a carriage structure 31 (Figs. 1, 2, 3, 4, 8, 9 and 12). This carriage structure, as shown most clearly in Fig. 8, is of triangular configuration. The support 27 may be attached to the top of the carriage structure 31 as by the aid of

the screws 32 (Figs. 2 and 8), which pass through a flange on the bottom of the downwardly extending column 33 of the support 27. This column is shown as passing downwardly through the slot 34 in the top member 21 (Figs. 1, 2 and 9).

The lower side of the carriage structure 31 may be provided with a plurality of rollers 35 freely rotatable on stub shafts anchored within ears provided in the frame 31. These rollers engage the carriage guide rods 36, 37 (Figs. 1, 2, 8 and 12) that are fixed to the frame members 9, 10 and 11. Three such rollers 35 may be utilized for this purpose; one immediately below the column 33, engaging the guide rod 37; and two spaced rollers at opposite ends of the frame 31, and engaging the guide rod 36.

A constraint is placed against lateral movement of the frame 31 with respect to the guide rods 36 and 37. Thus for example, the ear 38, serving as a pivot support for one of the rollers 35 that contacts with the guide rod 37, may serve as a support for a downwardly depending leaf spring 39, contacting the rod 37 and limiting carriage movement toward the left as viewed in Fig. 2. A similar spring restraint 40 may be utilized in connection with one of the rollers 35 that contacts with the guide rod 36; and a similar spring finger 41 (Fig. 12) may be utilized in connection with the other roller that contacts the guide rod 36. These spring fingers 40 and 41 restrain right hand movement of carriage 31 as viewed in Fig. 2.

The manner in which the carriage 31 is advanced radially outwardly in the direction of arrow 30 may now be described. For this purpose there is provided a lead screw 42 (Figs. 8, 9, 11 and 12). This lead screw 42 is shown as having an axis normal to the axis of the spindle 4. It is shown in Fig. 9 as being supported at its left hand end in a ball bearing structure 43. The outer race of this ball bearing structure is shown as supported in the boss 44 formed integrally with the side frame 10. The inner race of this ball bearing structure is held in place as by the aid of nuts 45 against a shoulder formed on the lead screw 42.

At its right hand end, as shown most clearly in Fig. 9, the lead screw 42 has a hollow extension 46 which serves to accommodate the inner race of a ball bearing structure 47. The outer race of this ball bearing structure is shown as supported in the intermediate frame 11. At the right hand end of the lead screw 42 a gear wheel 48 (Figs. 8, 9 and 10) may be provided. This gear wheel 48 is shown as provided with spiral teeth adapted to engage the spiral pinion 49 mounted on the spindle 4. Accordingly the lead screw 42 is rotated from power derived from the turntable spindle 4, and the angular motion of the screw 42 is proportional to the angular motion of the turntable 1. By appropriate design of the pitch of the threads of lead screw 42, and of the intermediate gearing, the pitch of the grooves produced on the record 2 may be made to conform with any desired value.

Rotation of lead screw 42 results in a corresponding traversing movement of the recorder head 23. This is accomplished by the aid of a nut structure carried by the frame 31. This nut structure is shown to best advantage in Figs. 8, 11, 12 and 13.

Thus the nut structure has a pair of interrupted bands 50, 51 that are internally threaded. These bands 50 and 51 are axially spaced, and are

joined by a yoke 52. These interrupted bands 50 and 51 occupy different angular portions of a complete circumference so as to engage the threads of lead screw 42 on diametrically opposite sides thereof. In this way, a rotation of the yoke 52 about an axis 53 radial to the axis of the screw 42, serves either to engage or disengage the interrupted bands 50 and 51 with respect to the screw 42.

In order to permit this rotation, as well as to connect the nut structure operatively to the carriage 31 so that the carriage 31 may be advanced in accordance with the motion of the nut structure, a shaft 59 is fastened to the yoke 52. This shaft is rotatable about the axis 53, as by being journaled in a guide 54, fastened as by screws 55 to a sloping face 56 on the frame 31. This guide 54 is provided with side flanges for the accommodation of the fastening screws 55, and overlies the aperture 57 (Fig. 12) in which the pin 58 of roller 35 is accommodated.

The shaft 59 is provided with a collar 60 at its upper end. Interposed between the collar 60 and the guide 54 is a compression spring 61 surrounding the shaft 59. This compression spring serves to keep the threaded band members 50 and 51 in proper contacts with the threads on the lead screw 42, and also permits the nut structure to accommodate itself accurately with respect to the screw 42.

The shaft 59 is resiliently urged in an angular direction to move the interrupted bands 50 and 51 into engagement with the lead screw 42. This may be accomplished for example, by the aid of a tension spring 62. One end of this tension spring passes around a post 63 mounted near the edge of the collar 60. The other end of spring 62 may be anchored to a pin 64 attached to the frame 31.

Should it be necessary to disengage the nut structure from the screw 42, the shaft 59 may be given a counterclockwise rotation as viewed from the top. The manner in which this may be accomplished will be described hereinafter. It is sufficient for the present to note that by virtue of the resilient elements 61 and 62, and by virtue of the angular adjustability of the nut structure about the axis 53, this nut structure can follow accurately the threads on screw 42, even if there should be some misalignment of the shaft 42; or even a slight bending of the shaft. No binding effect can result, since the connections permit a sufficient degree of freedom of movement of the nut structure to permit the threads to accommodate itself to these irregularities.

The manner in which the turntable 1 may be rotated may now be described, especially in connection with Figs. 2, 3, 8 and 9. The source of power for this rotation may be provided for by a small electric motor 65 (Fig. 8). This motor drives, through appropriate gearing, a shaft 66. This shaft carries a sheave 67 joined as by the belt 68 to a corresponding sheave 69. As shown most clearly in Fig. 9, this sheave 69 is shown as mounted on shaft 70 supported as by the aid of the ball bearing structure 71 in the frame member 8. The other end 72 of the shaft 70 is shown as journaled within the hollow extension 46 of the lead screw 42. Thus the lead screw 42 and shaft 70 are coaxial. The shaft 70 carries a driving element or member 73 in the form of a hollow metallic roller (Figs. 2 and 3). In driving relation with the periphery of roller 73 and with the under side of the table 1 is an idler wheel 74. This idler wheel may be provided with a resilient

or rubber rim 75. It may project through slot 76 in the cover member 21 so as to enable the rim 75 to be placed in contact with the lower surface of table 1.

As is apparent from a consideration of Figs. 2 and 3, the wheel 74 serves to transmit rotation from the roller 73 to the table 1, when it is disposed in the operative position shown in these figures. This wheel 74 is mounted on the carriage 31, so that as the carriage moves laterally, the wheel 74 contacts the table 1 at variable radii. Furthermore, as shown most clearly in Fig. 9, the wheel 74 is disposed immediately beneath the recording stylus 22. Since the peripheral speed of the wheel 74 is the same as the peripheral speed of roller 73, it is apparent that at all times the linear speed of recording is constant, and may be chosen to be of the order of 6 inches per second, as referred to in the prior application hereinbefore identified.

The manner in which the wheel 74 is mounted upon the carriage 31 may be best explained in connection with Figs. 2, 3, 4 and 8. Thus the wheel 74 may be freely rotatable upon a stationary stub shaft 76', which is supported on an arm 77. This arm 77 is slidably guided in the spaced guides 78 and 79 fastened to the top surface of the frame 31. For this purpose the arm 77 is made rectangular in cross section. The wheel 74 is urged resiliently toward the right and into driving relation by the aid of a tension spring 80. One end of this tension spring is anchored to the right hand end of the bar 77. Its other end may be anchored to an anchor pin 81 fastened to the carriage 31. In order further to guide the movement of the bar 77, this bar may be provided with a transverse slot 82 through which passes the screw 83, supported in the guide 79. Furthermore, near the left hand edge of the carriage 31, a rest 84 in the form of a transverse pin extends across the guide 78. When it is desired to disconnect the drive to the table 1, the bar 77 is moved toward the left, and it assumes the dot and dash position indicated in Fig. 3. The bar 77 then rests upon the transverse pin 84, and the wheel 74 is lowered out of contact with table 1.

Convenient means are provided for lifting the recording unit or head 23 off of the disk 2, and if desired also to stop rotation of the turntable 1. This action may occur in sequence; that is, it is possible to raise the recording head without stopping the turntable, as for example when it is desired to operate a playback mechanism hereinafter to be described. Alternatively, however, it is possible to disconnect the driving wheel 74 so as to stop rotation of the table 1. Optionally, also, it is possible to cause disengagement of the nut structure 50, 51 from the lead screw 42 to make it possible if desired to adjust the position of the recorder head 22 along the record disc 2.

The mechanism for accomplishing these effects is shown to best advantage in Figs. 2, 5, 8 and 11. Thus there is a vertical shaft 85 journaled in the support 27 and capable of manual manipulation as by the aid of knurled head 86. This shaft 85 passes across a cavity or recess 87 in the under side of the support 27. To the shaft 85 are fastened the eccentrics 88 and 89. The eccentric 88 is adapted to contact the rounded end of a push rod 90. This push rod 90 is slidably supported in the support 27 and has an enlarged rounded end 91. This enlarged rounded end 91 acts against the inner surface of an arm 92 fastened to the frame 24 and projecting downwardly

to cooperate with the member 91. The weight of the pivoted source 23, 24 acts to urge the push rod 90 against the periphery of the eccentric 89. When the eccentric 89 is in the position illustrated in Figs. 2 and 3, the stylus 22 is urged by gravity into contact with the disc 2. However, by rotation of the knurled head 86 the pivoted structure 23, 24 is raised by the force exerted toward the left through the push rod 90 upon the arm 92.

At the same time, eccentric 88 acts through the eccentric strap 93, link 94 and clevis 95 to operate a crank 96 (Fig. 5). This crank 96 is fastened to a vertical shaft 97 extending across a cavity 98 in the column 33. The ends of this shaft 97 are appropriately journaled in the end members of the column 33. Thus rotation of eccentric 88 thus rocks shaft 97.

Referring now to Fig. 8, shaft 97 is arranged to operate a link 98'. This link 98' is operated through the crank 99 fastened to the shaft 97. The left hand end of the link 98' operates upon a lever 100 pivoted on post 101. The free end of this lever 100 is arranged to cooperate with a pin 102 fastened to the top of the bar 77. However, there is lost motion between the lever 100 and the pin 102 as shown most clearly in Fig. 8. In this way it is assured that the recording head 23 may be raised without placing the driving wheel 74 out of operative relation. Upon continued rotation of the button 86, however, pin 102 is contacted by lever 100, bar 77 is moved toward the left, and the wheel 74 is urged to the inoperative position indicated by the dot and dash lines of Fig. 3.

Upon further continued rotation of the button 86 it is possible entirely to disengage the nut structure 50, 51 from the lead screw 42. In order to accomplish this result, the crank structure 89 carries another crank arm 103 which operates a link 104. This link 104 is connected at its upper end to crank arm 105 (Figs. 8, 11 and 12). This arm 105 is provided with a hub 106 pivotally supported on a post 107 supported on top of the carriage 101. When link 104 is urged upwardly upon rotation of shaft 97, the upper edge of arm 105 contacts the pin 63 on collar 60. In this way the shaft 59 is rotated in a counter-clockwise direction as viewed from a top of the shaft, and the threaded interrupted bands 50 and 51 are disconnected from the screw 52. When this is accomplished, the recorder head 22 may be moved along the record disk 2.

In addition to the recorder head 23 and recording stylus 22 there is provided a reproducing or play-back head 108 (Figs. 1, 6, 7, 9, 14 and 15). This play-back head as shown most clearly in Fig. 1, is arranged to traverse the record disk 2 along the direction of the arrow 109 transverse to the direction of movement of the recording head 23.

The play-back head 108 may also be of the electromagnetic variety, having a reproducing stylus 110. This stylus 110 may be permitted at will to rest by gravity upon the record 2. Thus for example the head 108 may be provided at its rearward end with an ear 111 (Figs. 14 and 15). This ear 111 is attached as by a screw 112 to a downwardly extending post 113. This post in turn is attached to a cross arm 114. This cross arm is pivotally supported in the ears 115 and 116 formed on a bracket 117. The weight of the head 108, thus pivotally supported, is sufficient to maintain stylus 110 in operative contact with disc 2.

This bracket 117 as shown most clearly in Figs. 6, 7, 14 and 16, is provided with a longitudinal rectangular recess, for sliding engagement with a stationary rectangular guide bar 118. It is supported by aid of a round end 120 within a slotted boss 119 (Figs. 6 and 7) formed integrally with a bracket 122. This bracket 122 is disposed adjacent the frame member 11 (Figs. 6 and 8) and is fastened to the frame structure as by the aid of the slotted ears 123 and 124 which embrace the frame bars 12 and 13. The upper end of bracket 122 passes through the slot 121 formed in the top 21.

The left hand end of the bar 118 as shown most clearly in Figs. 6 and 7, is accommodated in a recess 125 of an end plate 126. It may be held in the recess as by the set screw 127 (Fig. 6). The end plate 126 serves, with a similar opposite end plate 128, to support a sheet metal cover member 129 (Figs. 1, 6, 7 and 14). This sheet metal cover member as shown most clearly in Figs. 14 and 15, extends around the guide bar 118.

In order manually to lift the reproducer head 108 from the record disc 2 when desired, use is made of an eccentric rod 130 (Figs. 7, 14 and 15). This eccentric rod is journaled at its ends in the plates 126 and 128, and is provided at its left hand end with a knurled thumb piece 131 for manual operation. Upon rotation of the eccentric 130 from the position illustrated in Fig. 14, it is made to engage an arm 132. This arm 132 is fastened to a yoke 133 embracing the ears 115, 116, and pivoted thereto. The yoke 133 has downwardly extending arms 134 having ends contacting the back surface of head 108. When the eccentric 130 engages the arm 132 and urges it downwardly about the yoke pivot, the arms 134 urge the head 108 in a clockwise direction, as viewed in Fig. 14, and free of the record disc 2.

The traversing motion of the reproducing head 108 is made to follow the traversing motion of the recorder head 23. This is accomplished by the aid of a flexible element, cable, or cord 135 (Figs. 6, 7, 8, 14, 15, 17 and 19). The recording head or unit 23, as well as the reproducer head 108 are joined to this flexible element. This element is guided by appropriate guide pulleys, supported on certain of the frame members.

Thus for example the frame member 9 (Figs. 8 and 17) is provided with an integral ear 136 supporting a stationary boss 137. A guide pulley 138 for the flexible element 135 is mounted for free rotation upon a stub shaft supported on the boss 137. Similarly, the bracket 122 is provided with ears 139 and 140, similarly supporting the guide rollers 141, 142. The flexible element or cord 135 passes around the pulley 138 and to the pulleys 141 and 142. These pulleys guide both reaches of the flexible element 135 upwardly through apertures in the cover member 21 on to the guide pulleys 143 (Figs. 6 and 7) mounted for free rotation in the bearing blocks 144 fastened to the lower surface of the guide bar 118. These pulleys 143 guide the reaches to a position on opposite sides of bar 118, as shown most clearly in Fig. 7. Horizontal reaches of the flexible element 135 pass around the terminal pulley structure 145 accommodated in the slotted end 70 of the bar 118. One reach of the flexible element 135 is clamped to the reproducer head bracket 117 in a manner best illustrated by the aid of Figs. 14 and 16. Thus the bracket 117 is shown as having a slot 146 in its lower front edge. Across this slot the element 135 passes.

Engaging within the slot is a clamping member or jaw 147 contacting the lower side of the cable or flexible element 135 and urged to clamping position as by the aid of the screw 148.

Accordingly when the cable or flexible element 135 is moved as permitted by the various guide pulleys, the reproducing head 108 is caused correspondingly to traverse the record disc 2.

The ends of the flexible element 135 are shown in Fig. 17 as being joined by the tension spring 149.

The manner in which the recorder head structure 23 is attached to the cable element 135 is shown to best advantage in Figs. 2, 17 and 19. There is a vertical spindle 150 journaled in the column 33 and capable of manual manipulation by the aid of the head 151. This head 151, as shown most clearly in Fig. 18, is accommodated in an arcuate recess 152 in the edge of the support 27. The lower end of spindle 151 carries a wheel or pivoted member 153 which may have a pair of annular grooves 154 and 155. These grooves are each preferably wide enough to accommodate a plurality of turns of the flexible element 135 in side by side relation. Groove 154 is in position to accommodate that portion of the flexible element 135 which passes toward the left from the pulley 141. The level of the lower groove 155 is such as to cooperate with that portion of flexible member 135 which passes over the top of pulley 138. The flexible element 135 is wound several times around the wheel 153 in groove 154, whence it passes from groove 155 to groove 154 through a transverse passage 156 connecting the two grooves. The element 135 passes around groove 155 in the same direction as in groove 154. The several turns of the flexible element 135 around the wheel 153 thus serves as a mechanical connection between the flexible element and the recording head structure. Accordingly when the recording head structure is moved by the lead screw 42, the cable or flexible element 135 is likewise moved through the medium of shaft 150 and wheel 153, and the reproducing head 108 is moved coincidentally with the movement of the recording head 23.

Furthermore, by making it possible to rotate the shaft 150, the relative positions of the two heads with respect to the flexible element may be adjusted. For example, assuming that the head structure 23 is stationary, and that the spindle 150 is rotated in a clockwise direction as viewed in Fig. 1, this rotation causes the upper reach of cable 135 as viewed in Fig. 17 to move toward the left. The lower reach of the cable 135 around pulley 138 moves to the right. Accordingly that portion of flexible element 135 which is engaged on pulley 141 is pulled downwardly. Now considering Fig. 17, this means that the lower reach of flexible element 135 as seen in that figure, moves toward the right, that is, in a direction radially away from the center of the turntable spindle. Accordingly a clockwise rotation of spindle 150 causes reproducing head 108 to be urged outwardly with respect to the record disc 2. A reverse direction of rotation of spindle 150 will obviously cause the reproducer head 108 to move toward the left as viewed in Fig. 1, and thereby to lag the recorder head 23 on the recorder disc 2. The amount of lag can be adjusted by manipulation of the head 151 of the spindle 150. To facilitate this adjustment, use may be made of a graduated plate 167 (Figs. 2 and 18) having an arcuate edge cooperating with the head 151. This head may be provided

with an index mark or arrow 168 to cooperate with the graduations.

By appropriate setting of the lag of reproducer head 108 it is possible to reproduce the immediately preceding recorded matter at any time by simply lifting the recorder head 23, without disturbing the drive connections as heretofore explained, and by dropping head 108 to active position. Then by appropriate electrical switching, the reproducer head 108 may be placed into electrical operation. During recording the reproducing head 108 may be raised by appropriate manipulation of the knurled thumb piece 131.

It may be required to make it possible to set the reproducer head 108 so that it complies with a desired portion of the record disc 2. Logging cards may be used for this purpose, upon which may be indicated the material that is recorded. Thus for example the reproducer head bracket 117 may have a projection 157 (Figs. 7, 14 and 15) extending through a slot 158 in the guard member 129. Attached to the projection 157 may be a pointer 159. This pointer is intended to traverse a card 160 (Figs. 20, 21 and 22). This card 160 is shown as provided with graduations 161 cooperating with the pointer 159 and corresponding to constant time intervals of the record. Opposite these graduations may be appropriate identifying matter to indicate what is recorded adjacent these graduations on the record corresponding to the card in use.

The card 160 may be utilized, during the process of recording, for notations of the recorded material, since the pointer 159 also corresponds to the position of the recorder head 23.

The card 160 may be held approximately in place on an extended shelf 162 (Figs. 14 and 20) as by the aid of several spring fingers 163, 164. A corner guide 165 may be provided for the lower corner of the card and an additional guide 166 at the lower right hand corner may be provided.

What is claimed is:

1. In a phonograph mechanism including a record, a recording head and a reproducing head for cooperating with the record, a carriage for each of said heads, guide means for each of said carriages to cause the associated head to move transversely of the record, means for moving one of said carriages on its guide, and a flexible element connecting the carriages to maintain the heads in predetermined relationship with respect to the record, said guide means being so arranged as to cause the heads to move in paths substantially perpendicular to each other.

2. In a phonograph mechanism including a record, a recording head and a reproducing head for cooperating with the record, a carriage for each of said heads, guide means for each of said carriages to cause the associated head to move transversely of the record, means for moving one of said carriages on its guide, a flexible element connecting the carriages to maintain the heads in predetermined relationship with respect to the record, said guide means being so arranged as to cause the heads to move in paths transverse to each other, and means operating upon said flexible element, for adjusting the relationship of the heads.

3. In a phonograph mechanism including a record, a recording head and a reproducing head for cooperating with the record, a carriage for each of said heads, guide means for each of said carriages to cause the associated head to move transversely of the record, means for moving one of said carriages on its guide, a flexible element

connecting the carriages to maintain the heads in predetermined relationship with respect to the record, said guide means being so arranged as to cause the heads to move in paths transverse to each other, a member pivoted on one of said carriages, to which member the flexible element is connected, and means to adjust said member about its pivot, whereby the position of said element may be optionally adjusted with respect to the said one carriage, and limited movement imparted to one of said heads independently of the other head.

4. In a phonograph mechanism including a record, a recording head and a reproducing head for cooperating with the record, a carriage for each of said heads, guide means for each of said carriages to cause the associated head to move transversely of the record, means for moving one of said carriages on its guide, a flexible element connecting the carriages to maintain the heads in predetermined relationship with respect to the record, said guide means being so arranged as to cause the heads to move in paths substantially perpendicular to each other, and means including an adjustable wheel over which said element passes, for altering the relationship of the heads.

5. In a phonograph mechanism including a record, a recording head and a reproducing head for cooperating with the record, a carriage for each of said heads, guide means for each of said carriages to cause the associated head to move transversely of the record, means for moving one of said carriages on its guide, a flexible element connecting the carriages to maintain the heads in predetermined relationship with respect to the record, and means including an adjustable wheel carried on one of said carriages and about which said element passes, for altering the relationship of the heads.

6. In a phonograph mechanism including a record, a recording head and a reproducing head for cooperating with the record, a carriage for each of said heads, guide means for each of said carriages to cause the associated head to move transversely of the record, means for moving one of said carriages on its guide, a flexible element passing over guide pulleys and connecting said carriages for corresponding movement, a pivoted

member secured in adjustable manner to one of said carriages, said element being secured to said member, and means to adjust said member about its pivot, whereby the position of said carriage with respect to the element is altered.

7. In a phonograph mechanism including a record, a recording head and a reproducing head for cooperating with the record, a carriage for each of said heads, guide means for each of said carriages to cause the associated head to move transversely of the record, means for moving one of said carriages on its guide, and a flexible element connecting the carriages to maintain the heads in predetermined relationship with respect to the record, one of said carriages rotatably carrying a wheel to which said element is secured, rotation of the wheel serving to adjust the position of the carriage with respect to the flexible element.

20 8. In a phonograph mechanism including a record, a recording head and a reproducing head for cooperating with the record, a carriage for each of said heads, guide means for each of said carriages to cause the associated head to move transversely of the record, means for moving one of said carriages on its guide, a flexible element connecting the carriages to maintain the heads in predetermined relationship with respect to the record, one of said carriages rotatably carrying a 25 wheel to which said element is secured, rotation of the wheel serving to adjust the position of the carriage with respect to the flexible element, and an indicator for showing the position of said wheel on its axis, whereby the relative position 30 of the heads is indicated.

35 9. In a phonograph mechanism including a record, a recording head and a reproducing head for cooperating with the record, a carriage for each of said heads, guide means for each of said carriages to cause the associated head to move transversely of the record, means for moving one of said carriages on its guide, a flexible element connecting the carriages, guide pulleys for said element, and means for optionally causing said element to move about at least some of said 40 guide pulleys while said one carriage remains stationary.

FRANK RIEBER.
